Primary Examiner — Karen S Acker*Assistant Examiner* — Jonathan E Fiencke(74) *Attorney, Agent, or Firm* — Kanika Radhakrishnan; Evergreen Valley Law Group(57) **CLAIM**

The ornamental design for a water cup for poultry, as shown and described.

DESCRIPTION

FIG. 1 illustrates a perspective view of a water cup for poultry;

FIG. 2 illustrates a front elevation view thereof;

FIG. 3 illustrates a rear elevation view thereof;

FIG. 4 illustrates a right-side elevation view thereof;

FIG. 5 illustrates a left-side elevation view thereof;

FIG. 6 illustrates a top plan view thereof;

FIG. 7 illustrates a bottom plan view thereof;

FIG. 8 illustrates the front elevation of the water cup for poultry in a position of use;

FIG. 9 illustrates the rear elevation view thereof; and,

FIG. 10 illustrates the left-side elevation view thereof.

The broken lines in FIGS. 8-10 depict the environmental structure of a water dispensing nipple that forms no part of the claimed design.
